Fig. 2.

Fig. 3.

Inventor:
Samuel Buchsbaum
By: May W Zabel Atty.

UNITED STATES PATENT OFFICE.

SAMUEL BUCHSBAUM, OF CHICAGO, ILLINOIS.

BELT BUCKLE.

Application filed February 3, 1923. Serial No. 616,794.

To all whom it may concern:

Be it known that I, SAMUEL BUCHSBAUM, a citizen of the United States, residing at Chicago, in the county of Cook and State 5 of Illinois, have invented a certain new and useful Improvement in Belt Buckles, of which the following is a full, clear, concise, and exact description, reference being had to the accompanying drawings, forming a 10 part of this specification.

My invention relates to belt buckles, and more particularly to a simple form of belt buckle which comprises a gripping member and a member for moving said gripping 15 member into and out of gripping relationship with a belt.

It is a further purpose of the invention to provide a belt buckle comprising a front plate and a gripping member for clamping 20 one end of a belt between itself and the front plate, and a member for holding the other end of the belt, said members being provided with pivot means entering the same pivot openings provided in the front 25 plate, said pivot openings being preferably in rearwardly extending side flanges on said front plate.

Other objects and advantages of the invention will appear as the description of 30 the accompanying drawings proceeds. However, I desire to have it distinctly understood that I do not intend to limit myself to the exact details shown or described, but that I intend to include as part of my 35 invention all such obvious changes and modifications of parts as would occur to a person skilled in this art and as would fall within the scope of the claims:

In the drawings:

Fig. 1 is a rear elevational view of a belt buckle showing the ends of a belt connected therewith;

Fig. 2 is an edge view thereof; and

Fig. 3 is a section taken on the line 3—3 45 of Fig. 1.

Referring in detail to the drawings, in Figs. 1 and 2 is shown a belt 5 having an end portion 6 secured to the body portion 5 thereof to form a loop 7, said end portion 50 being secured to the belt 5 by any suitable securing means 8. The loop 7 at one end of the belt 5 engages with a loop 9 provided on the member 10 which is pivotally mounted in openings 11 in the side flanges 12 of 55 the front plate 13 of the buckle. Each side

flange 12 is provided with one pivot opening 11 and a lug 14 extending laterally from each side of the member 10 engages in one of said openings. A belt end clamping member 15 is provided with lugs 16, similar 60 to the lugs 14, which also extend into said openings 11, thus each opening 11 has two lugs 14 and 16 extending into the same to form a divided pivot pin for the buckle at each side thereof. The side flanges 12 have 65 ears 17 thereon, which extend substantially parallel to the front plate 13 and form guides for the free end of the belt 18. The belt end 18 extends between the gripping member 15 and the rear side of the front 70 plate 13, and in the form shown said gripping member is made substantially V-shaped having a pair of legs 19 and 20 extending at an acute angle to each other, the leg 19 being longer than the leg 20, as will be clear 75 from Fig. 3. The bight portion 21 of said member 15 connecting the portions 19 and 20 rests in a groove or recess 22 provided in the member 10, said member 10 having a substantially U-shaped portion 23 providing 80 said groove 22 and forming a shoulder 24 between the same and the main body portion of the member 10, and a shoulder 25 at the free end thereof.

It will be seen from Fig. 3 that the angle 85 which the members 19 and 20 have to each other is sharper, or more acute than the angular relationship of the portions 25 and 24, thus the member 15 has a small amount of play or an independent pivotal or rocking motion relative to the member 10, and it will be evident from Fig. 3 that when the member 10 is swung toward the front plate or counterclockwise in Fig. 3, the shoulder 90 24 will engage with the leg 19 of the member 15 and move the member 15 into gripping relation to the belt. The leg 20 will first engage with the belt and upon a pull being exerted on the belt toward the left the lower member 19 will move into gripping engagement relative to said belt end 18. If it is desired to disengage the gripping member from the belt end 18, all that is necessary is to move the member 10 in a clockwise direction when the shoulder 25 at 95 the free end will engage with the member 20 on the member 15, thus swinging the gripping member 15 out of gripping engagement relative to the belt end 18, after 100 which the end 18 can be readily slipped out 105 110

- of the belt buckle. It will thus be seen that a belt buckle is provided which has a member for clamping one end of the belt in adjusted position, and a member for holding 5 the other end of the belt or to which the other end of the belt is secured, both of said members having lugs, which together make up the pivot pins for the buckle parts that are movable, said pivot pins extending 10 through openings in the side flanges of the front plate and that a belt buckle of this type is provided which comprises a pair of parallel gripping edges 26 and 27 provided on the legs 19 and 20, one of which is further 15 away from the pivot point than the other, said belt end gripping member being moved into and out of gripping position by an operating member which has the other end of the belt secured thereto.
- 20 It will be further noted that a very simple construction of belt buckle is provided comprising only three parts, the front plate with its side flanges, the gripping member with its pivot lugs and the operating member carrying the other end of the belt with 25 its pivot lugs, thus providing a simple and cheaply constructed device, which is positive in operation.
- Having thus described my invention, what 30 I desire to claim and secure by U. S. Letters Patent is:
1. A belt buckle of the character described, comprising a front plate having a pair of pivot openings therein, a belt gripping member and a member for moving said belt gripping member into belt engaging position, said gripping member having independent movement relative to said last member, both said members having pivot means 35 entering said openings.
  2. A belt buckle of the character described, comprising a front plate provided with a pair of flanges having pivot openings therein, a belt gripping member and a member for moving said belt gripping member into belt engaging position, said gripping member having independent movement relative to said last member, both said members having pivot means entering each of said 40 openings.
  3. A belt buckle of the character described, comprising a front plate having a pair of pivot openings therein, a belt gripping member and a member for moving said belt gripping member out of belt engaging position, said gripping member having independent movement relative to said last member, both said members having pivot means entering said openings.
  4. A belt buckle of the character described, comprising a front plate having a pair of pivot openings therein, a belt gripping member and a member for moving said belt gripping member into and out of belt 45 engaging position, said gripping member

having independent movement relative to said last member, both said members having pivot means entering said openings.

5. A belt buckle of the character described, comprising a front plate having 70 pivot openings therein, a belt gripping member and a member for moving said belt gripping member into belt engaging position, said gripping member having independent movement relative to said last member, both 75 said members having pivot means entering each of said openings, said belt gripping member having a plurality of parallel gripping edges.

6. A belt buckle of the character de- 80 scribed, comprising a front plate having pivot openings therein, a belt gripping member and a member for moving said belt gripping member into belt engaging position, both said members having pivot means en- 85 tering each of said openings, said belt gripping member having a plurality of parallel gripping edges, one of said gripping edges being further from its pivots than the other 90 thereof.

7. A belt buckle of the character de- 95 scribed, comprising a front plate having pivot openings therein, a belt gripping member and a member for moving said belt gripping member into belt engaging position, both said members having pivot means en- 100 tering said openings, said member for moving said belt gripping member into gripping position having a recess for receiving said gripping member.

8. A belt buckle of the character de- 105 scribed, comprising a front plate having pivot openings therein, a belt gripping member and a member for moving said belt gripping member out of belt engaging position, said gripping member having independent movement relative to said last member, both 110 said members having pivot means entering each of said openings, said belt gripping member having a plurality of parallel gripping edges.

9. A belt buckle of the character de- 115 scribed, comprising a front plate having pivot openings therein, a belt gripping member and a member for moving said belt gripping member into belt engaging position, both said members having pivot means en- 120 tering said openings, said member for moving said belt gripping member into gripping position having a recess for receiving said gripping member.

10. A belt buckle of the character de- 125 scribed, comprising a front plate having pivot openings therein, a belt gripping member and a member for moving said belt gripping member out of belt engaging position, both said members having pivot means en- 130 tering each of said openings, said belt gripping member having a plurality of parallel gripping edges, one of said gripping edges

being further from its pivots than the other thereof.

11. A belt buckle of the character described comprising a front plate having pivot openings, a member for holding one end of a belt having pivot lugs entering said openings, and a member for clamping the other end of said belt against said front plate having pivot lugs also entering said openings said members having independent relative movement.

12. A belt buckle of the character described comprising a front plate having a pair of side flanges each having a pivot opening therein, a member for holding one end of a belt, a pair of pivot lugs on said member each entering one of said openings, a member for clamping the other end of said belt against said front plate, and a pair of pivot lugs on said last member each entering one of said openings said members having independent relative movement.

13. A belt buckle of the character described, comprising a front plate, a belt gripping member having a pair of diverging legs pivotally mounted thereon, and an operating member embracing said gripping member and having a groove therein in which said gripping member seats.

14. A belt buckle of the character described, comprising a front plate, a belt gripping member having a pair of diverging legs pivotally mounted thereon, and an operating member embracing said gripping member and having a groove therein in which said gripping member seats, said groove having diverging walls extending at a greater angle to each other than said legs.

15. A belt buckle of the character described, comprising a front plate, a substantially V-shaped belt gripping member mounted thereon, and an operating member embracing said gripping member and having a substantially V-shaped groove therein in which said gripping member seats.

16. A belt buckle of the character described, comprising a front plate, a substantially V-shaped belt gripping member mounted thereon, and an operating member embracing said gripping member and having a substantially V-shaped groove therein in which said gripping member seats, said groove being wider than said gripping member.

In witness whereof, I hereunto subscribe my name this 18th day of January A. D., 1923.

SAMUEL BUCHSBAUM.
